[57] **CLAIM**

The ornamental design for a padlock and latch protector, as shown and described.

DESCRIPTION

FIG. 1 is a back elevational view of a padlock and latch protector showing a first embodiment of our new design; FIG. 2 is a front elevational view thereof;

FIG. 3 is a top plan view thereof, with the bottom plan view appearing as a mirror image of the top plan view;

FIG. 4 is a right end view thereof, with the left end view appearing as a mirror image of the right end view; and,

FIG. 5 is a back elevational view of a padlock and latch protector showing a second embodiment of our new design shown in reduced scale from the first embodiment;

FIG. 6 is a front elevational view thereof;

FIG. 7 is a top plan view thereof, with the bottom plan view appearing as a mirror image of the top plan view; and,

FIG. 8 is a right end view thereof, with the left end view appearing as a mirror image of the right end view.
